UNITED STATES PATENT OFFICE.

FREDRICK C. GENGE, OF CHICAGO, ILLINOIS, ASSIGNOR TO THE MARSHALL VENTILATED MATTRESS COMPANY, OF CHICAGO, ILLINOIS, A CORPORATION OF ILLINOIS.

CUSHION OR MATTRESS.

1,321,095.

Specification of Letters Patent. Patented Nov. 11, 1919.

Application filed October 25, 1917. Serial No. 198,386.

To all whom it may concern:

Be it known that I, FREDRICK C. GENGE, a citizen of the United States, and a resident of Chicago, in the county of Cook and State 5 of Illinois, have invented certain new and useful Improvements in Cushions or Mattresses; and I do hereby declare that the following is a full, clear, and exact description thereof, reference being had to the accompanying drawings, and to the letters of 10 reference marked thereon, which form a part of this specification.

This invention relates to improvements in spring cushions or mattresses and consists of 15 the matters hereinafter described and more particularly pointed out in the appended claims.

The object of the invention is to produce a cushion or mattress which is cheap to 20 manufacture, easy to assemble and which is efficient in operation for its intended purposes. These objects as well as the many advantages of my invention will be made more apparent as I proceed with my specification.

In illustrating my invention, I have shown it as applied to a cushion and more particularly to a cushion of the kind adapted and intended for use as a seat cushion for automobiles or other vehicles, but it will be manifest that the features of the invention will also be of advantage in connection with 30 cushions or mattresses for other uses.

In the drawings:

35 Figure 1 is a perspective view of a seat cushion embodying the features of my invention, with a part of the outer covering broken away to more clearly show the interior construction thereof.

40 Fig. 2 is a view representing a vertical section through the cushion, in a plane indicated by the line 2-2 of Fig. 1.

Fig. 3 is a perspective view showing a part of a row of springs in their separate 45 pockets, used in my improved cushion.

Fig. 4 represents, on an enlarged scale, a bottom plan view of my improved cushion.

Fig. 5 is an enlarged, detail, perspective view showing the manner in which the covering is attached to the bottom frame.

50 Referring now in detail to that embodiment of my invention illustrated in the accompanying drawings:—15 indicates the cushion or mattress as a whole. It comprises a base 16, a body 17, supported on

said base and an outer covering 18 which encloses the body and holds it in position upon said base.

The base 16 of the cushion or mattress consists of a wire border frame 19 which defines and outlines the bottom plan of the cushion or mattress, of parallel, spaced, longitudinally extending wires 20, and of parallel spaced, transversely extending wires 21, connected to said border frame 19, which 60 form a grill-like platform upon which the body 17 is supported.

The body 17 consists of a plurality of springs 22 which are preferably arranged in rows 22^a. Each spring is inclosed in a 70 pocket 23, the pockets of the several springs in each row being connected together in the manner described in Letters Patent No. 685,160. All of the rows of pockets, are in themselves, inclosed in an envelop or casing 75 24, there being top and bottom frame wires 25, 26, respectively, in said envelop or casing which maintain the body as a whole in its proper form or shape. Thus the body 17 is a unitary structure in itself, capable of 80 being made in lots, each convenient for handling and ready for easy assembly upon the base 16 during the building up of each particular cushion or mattress 15.

The covering 18 which may be of any suitable material such as canvas, leather or the like, not only gives the proper finished appearance to the cushion or mattress as a whole, but acts to secure the body 17 against displacement in any direction upon the base 90 16. This covering comprises outer and inner members 27 and 28 between which is placed a wadding 29. A layer of curled hair or the like, 30, is preferably interposed between the top of the casing 24 and the inner 95 member 28 of the covering 18. As shown in this instance, the outer and inner members 27 and 28 of the covering material 18 extend from the top rear edge of the cushion over the top of the body and then downwardly in the form of an upright wall over the front face of the body 17. The side and rear walls 18^a, 18^a and 18^b respectively, are preferably not padded, as in the case of the 100 said upright front wall.

The bottom edges of said upright walls or aprons, terminate in substantially the plane of the base, said bottom edges being welted or rolled in a familiar manner. Clips 31 105 are provided which are bent about the border 110

frame and the adjacent part of the welted edge of the upright walls of the covering, in a manner securely attaching said upright walls to said border frame of the base 16. 5 (See Fig. 5).

My improved cushion is easily assembled. A body 17 is placed upon a base 16, a covering 18 is then draped or placed upon the body in the usual manner, and the clips 31 10 are then applied to attach the bottom edges of the upright walls of the covering 18 to the border frame 19 of the base.

The advantages of my improved cushion will be apparent to those familiar with the 15 art. It is sanitary, light in weight as against other constructions of cushions of the same size, and may be easily assembled in a short time by labor not necessarily skilled in the art.

20 While in describing my invention, I have referred to certain details of construction and arrangement of parts, I do not wish to be limited thereto, except as may be pointed out in the appended claims.

25 I claim as my invention:

1. A cushion or mattress comprising a 30 spring structure having a plurality of springs, a supporting bottom for said spring structure and separate and independent of the said structure, including a metallic border frame and cross wires connecting the sides and ends of said frame, a covering for the spring structure separate therefrom and having flexible side walls, the bottom edges 35 of which are arranged in the plane of the supporting bottom, and metallic clips for attaching said bottom edges to said bottom.

2. A cushion or mattress comprising a 40 spring structure having a plurality of springs, strips arranged in parallel rows, a spring inclosed in each one of a series of independent pockets in each strip, a casing having flexible side walls inclosing said spring structure separate and distinct from

the structure, a supporting bottom for said 45 structure, separate and distinct therefrom, said bottom comprising a wire border frame and means for attaching the lower edges of said side walls to the border frame.

3. A cushion or mattress comprising a 50 plurality of springs arranged in parallel rows, each spring being inclosed in one of a series of independent pockets each connected in a row, a casing inclosing said parallel rows of pockets, frames defining the top and 55 bottom ends of said casing, a base for said pocket-inclosing casing, said base including a wire border frame and cross wires connecting the sides and ends of said border frame, a layer of wadding on the top of said 60 casing, and an outer covering for said wadding and casing, said covering including an upright wall having a bottom edge, and clips attaching said bottom edge to the border frame of said base. 65

4. A cushion or mattress comprising a 70 plurality of springs arranged in parallel rows, each spring being inclosed in one of a series of independent pockets, each connected in a row, a casing inclosing said parallel rows of pockets, a base for said pocket-inclosing casing, said base including a wire border frame and cross wires connecting the sides and ends of said border frame, a layer of wadding on the top of said 75 casing, an outer covering for said wadding and casing, said covering including an upright wall having a welted bottom edge, and clips for attaching said welted edge to said border frame. 80

In testimony, that I claim the foregoing as my invention I affix my signature in the presence of two witnesses, this 23rd day of October A. D. 1917.

FREDRICK C. GENGE.
